Primary Examiner — Keli L Hill(74) *Attorney, Agent, or Firm* — DeLio Peterson & Curcio LLC; Thomas E. Ciesco(57) **CLAIM**

The ornamental design for a “speaker,” as shown and described.

DESCRIPTION

FIG. 1 is a right front top perspective view of the “speaker” design according to our invention;
FIG. 2 is a front elevational view of the “speaker” shown in FIG. 1;
FIG. 3 is a rear elevational view of the “speaker” shown in FIG. 1;
FIG. 4 is a bottom plan view of the “speaker” shown in FIG. 1;
FIG. 5 is a left side elevational view of the “speaker” shown in FIG. 1;
FIG. 6 is a right side elevational view of the “speaker” shown in FIG. 1; and,
FIG. 7 is a top plan view of the “speaker” design shown in FIG. 1.

The broken lines shown are included for the purpose of illustrating portions of the speaker that form no part of the claim.
